(57) **CLAIM**

We claim the ornamental design for an aerosol generator, as shown and described.

DESCRIPTION

FIG. 1 is a front perspective view of an aerosol generator according to an embodiment.

FIG. 2 is a back perspective view of the aerosol generator of FIG. 1.

FIG. 3 is a front view of the aerosol generator of FIG. 1.

FIG. 4 is a back view of the aerosol generator of FIG. 1.

FIG. 5 is a right side view of the aerosol generator of FIG. 1.

FIG. 6 is a left side view of the aerosol generator of FIG. 1.

FIG. 7 is a top view of the aerosol generator of FIG. 1; and,

FIG. 8 is a bottom view of the aerosol generator of FIG. 1. The broken lines showing portions of the aerosol generator are included for the purpose of illustrating portions of the article and form no part of the claimed design.
